Atty.

UNITED STATES PATENT OFFICE.

WILLIAM H. FULLINGTON, OF CLEVELAND, OHIO.

METHOD OF MAKING HANDLES FOR ROPES.

Application filed September 7, 1921. Serial No. 498,967.

To all whom it may concern:

Be it known that I, WILLIAM H. FULLINGTON, a citizen of the United States, residing at Cleveland, in the county of Cuyahoga and State of Ohio, have invented certain new and useful Improvements in Methods of Making Handles for Ropes, of which the following is a specification.

This invention relates to skipping ropes, and involves or includes a new process of making the handles thereof, and altho particularly adapted for making skipping ropes it is applicable to other ropes where it is desired to form an enlargement or bound portion at the end of the rope.

In making skipping ropes, and in staying the ends of a rope, it is common to wind the rope with a binding of small cord. This is done after the rope is made. By the present invention the binding is accomplished in an operation continuous with the formation of the rope.

The invention is illustrated in the accompanying drawings in which Figure 1 is a plan of a completed rope. Figs. 2 and 3 are views showing the rope in the process of construction. Fig. 4 is a section on the line 4—4 of Figs. 2 and 3. Figs. 5 and 6 are sections on the lines 5—5 and 6—6 of Figs. 1 and 3 respectively.

The manner of making the rope is as follows:

A rope consisting of four (or any other plural number) of strands is twisted in the usual manner, and of these strands three are indicated at 6 in the drawings, and these strands form the complete or standing part of the rope after it is completed. The fourth strand, which is indicated at 7, forms the handles. This strand, after all the strands are twisted together is severed at the middle of the rope, as indicated in Fig. 2, and then the ends of this severed strand are forced back or outwardly over the remaining three strands by a pressing action parallel to the axis of the rope, which results in the strand 7 being "fullled up" to the form of a coil, and these coils constitute the enlargement or handles, when they are pressed or stripped out to the ends of the rope. In Fig. 2 the strand 7 is shown at the commencement of

this operation, having been cut to make two free ends, and in Fig. 3 the process is shown partly completed, the coils being forced outwardly toward the ends of the rope, the strand being picked up from the twisted rope and assuming the form of a closed coil which gathers additional windings as it approaches the ends of the rope until it is finally stopped at said ends as by metal rings or fastenings 10 at the ends. The completed coil or winding is indicated at 7^a in Fig. 1, and the free ends thereof may be spliced into the standing strands 6 or otherwise fastened by any convenient device to prevent unwinding. The coil or winding thus produced forms a very convenient flexible handle and also acts to bind the ends of the rope. The operation may be rather quickly performed by "stripping" the severed strands along the rope until it fulls up to the completed coils at the ends.

I claim:

1. A rope consisting of a plurality of strands, one of said strands being severed and fullled up to form a binding coil at the end of the rope.

2. A skipping rope composed of a plurality of strands, one of said strands being severed and fullled up in the form of coils around the ends of the rope, thereby forming handles.

3. The method of forming a binding at the end of a rope, comprising severing one of the strands of the rope and fulling the same up in the form of a coil at the end of the rope.

4. The method of making handles for a skipping rope, comprising severing one of the strands of the rope and fulling the sections of said strand up to opposite ends of the rope, forming close coils around the remaining strands of the rope at said ends.

5. The method of making a skipping rope, comprising twisting a plurality of strands together, severing one of said strands, at about the middle of the rope, and fulling up the severed sections of said strand from the middle toward the ends of the rope, thereby forming coils around the ends of the rope, said coils serving as handles.

6. The method of binding the end of a

rope composed of a plurality of twisted strands, comprising severing one of the strands and forcing the severed strand along the rope toward the end of the latter, there-
5 by lifting said strand out of the twist and fulling the same up in the form of a coil around the end of the rope.

In testimony whereof, I do affix my signature in presence of two witnesses.

WILLIAM H. FULLINGTON.
